UNITED STATES PATENT OFFICE.

AMOS POST AND WILLIAM O'BRIEN, OF CATSKILL, NEW YORK.

ACETYLENE-GAS GENERATOR.

SPECIFICATION forming part of Letters Patent No. 631,476, dated August 22, 1899.

Application filed February 11, 1899. Serial No. 705,277. (No model.)

To all whom it may concern:

Be it known that we, AMOS POST and WILLIAM O'BRIEN, citizens of the United States, residing at Catskill, in the county of Greene and State of New York, have invented a new and useful Acetylene-Gas Generator, of which the following is a specification.

Our invention relates to an acetylene-gas generating apparatus, and has for its object 10 to provide simple and improved means for controlling the supply of liquid to the generator, while preventing the escape of gas at a normal pressure or when the pressure does not exceed a predetermined limit, and, furthermore, to provide, in connection with the liquid-feeding devices, a relief or blow-off, which while normally sealed is adapted to be exposed by the excess of gas-pressure to allow the escape of such excess. 15 Further objects and advantages of this invention will appear in the following description, and the novel features thereof will be particularly pointed out in the appended claims. 20

In the drawings, Figure 1 is a side view, partly in section, of a gas-generating apparatus constructed in accordance with our invention. Fig. 2 is a vertical sectional view of the gasometer and tank and a connected generator. Fig. 3 is a detail view of the liquid-feeding devices. 25

Similar reference characters indicate corresponding parts in all the figures of the drawings.

1 designates a gasometer-tank, and 2 a floating gasometer mounted therein in accordance with the general practice, the lower edge of the gasometer, which is concealed by the liquid contents of the tank, being provided, preferably, with antifriction guide-rollers 3, which traverse the inner surface of the wall of the tank. Arranged at opposite sides and exteriorly of the tank and preferably at diametrically opposite points are vertical tubular guides 4 and 5, which preferably extend through lateral ears 6 at the upper edge of the tank, and carried by the gasometer are ears 7, which are mounted to slide upon said guides to maintain the upper end of the gasometer in its proper position with relation to the tank, or, in other words, in its proper path of movement. In the construction illus-

trated these tubular guides 4 and 5 consist of pipes, of which the latter, which forms an outlet-conveyer, communicates at its upper end with a gas-main 8, while connecting the upper end of the former with the latter is a cross-pipe 9, forming a transverse brace. At an intermediate point the standard 4 is provided with a closed union 10, by which an upper pipe-section, forming one member of said standard, is connected with a lower pipe-section 4^a, constituting an inlet-pipe, and connected, respectively, with the lower ends of the inlet-pipe 4^a and the outlet-pipe 5 are inlet and outlet pipe extensions 11 and 12, constituting cooling-conductors and extending upward through the water or other liquid contents of the tank to a point above the plane of the surface of the liquid. In the construction illustrated the lower ends of the pipes 4^a and 5 are connected by a transverse pipe 13, having separate sections connected by a closed union 14, said sections being respectively in communication with the cooling-conductors 11 and 12. 75

The generator proper consists of any desired number of receptacles 15, connected by branch pipes 16 with a generator-pipe 17, said branches being provided with valves 18, having vents 19, and this generator-pipe is upheld to support the receptacles by means of uprights 20, consisting of stand-pipes or the equivalents thereof. Also in practice each receptacle is provided with a sectional top 21, 80 of which the central member 22 is removable and is connected with the branch pipe 16, a suitable fastening device being employed to support the receptacle in operative relation with said removable member or cover. For instance, the branch pipe is provided with a cross-bar 23 and the stationary portion of the receptacle-top with upstanding ears 24, having nuts 25 in which are threaded bolts 26, which extend downward from the ends of the cross-bar 23. Obviously by tightening these bolts the receptacle may be drawn upward into gas-tight contact with the cover 22, forming the removable member of the receptacle-top. The generator-pipe 17 is connected at one end with 85 a conveyer 27, which extends to and communicates with the inlet-pipe 4^a, and in communication with the other end of said generator-pipe is a liquid-feeding mechanism forming 90 95 100

one feature of our improved generating apparatus. This feeding device consists of a plurality of traps connected in series—namely, with the ascending or discharge arm of one trap connected with the descending or inlet arm of the next and with the ascending or discharge arm of one of the terminal traps in communication with the generator-pipe 17 and the descending or inlet arm of the other terminal trap in communication with a liquid-receiving funnel 28. In the construction illustrated only two traps 29 and 30 are shown, the descending or inlet arm of the trap 30 having the funnel 28 in communication therewith and the ascending or discharge arm of the other trap 29 being in communication with the generator-pipe; but communicating with the two traps at their point of connection or at the upper end of the descending arm of the trap 29 is a relief or blow-off pipe 31, which, however, is sealed by the contents of the trap 29, and hence can be in communication with the generator-pipe only when the liquid contents of the trap 29 have been forced out and into the trap 30 by the pressure of gas in the generator-pipe. It will be seen that by employing a plurality of traps arranged in series as described an excessive pressure of gas in the generator-pipe sufficient to back water out of the main trap 29, and thus allow the escape of the surplus or excessive pressure in the generator-pipe, will not discharge the contents of the auxiliary trap 30, and therefore upon the reduction of the pressure in the generator-pipe to a normal tension the contents of the auxiliary trap will be in a position to reseal the relief-tube 31, and thus prevent lowering the pressure in the generator-pipe below normal. To insure this operation, the inlet or descending arm of the auxiliary trap 30 is extended above the horizontal plane of the point of communication of the relief-tube with the traps, thus locating the funnel 28 at a considerable elevation above the point of connection of the two traps; but this extension of the inlet or descending arm of the auxiliary trap will control the normal pressure of gas in the generator. In other words, by extending said inlet-arm to a greater or less length the amount of pressure in the generator necessary to displace the contents of the main trap will be correspondingly varied, and therefore it is possible by the length of the inlet or descending arm of the auxiliary trap to control the normal pressure of gas desired in the generator, such pressure obviously being well within the tested strength of the retorts or receptacles constituting the generator.

The supply of liquid, as water, to the funnel, as in other devices of this class, is controlled by the position of the gasometer; but that form of the apparatus which we prefer to employ embodies a supply-reservoir 32, located exteriorly of the gasometer-tank, a flexible feed-tube 33, of rubber or equivalent material, having a terminal petcock 34 and a pendent bracket 35, carried by the gasom-

eter and supporting said feed-tube at a point near its extremity to cause the feed-tube to form a gooseneck or trap, with its discharge end in a pendent position over the funnel.

With this arrangement of parts the operation of the apparatus is as follows: When the gasometer is full, the discharge end of the feed-tube is elevated, as indicated in dotted lines in Fig. 2, to prevent outflow from the reservoir 32; but as the contents of the gasometer become exhausted to allow the descent thereof the discharge end of the feed-tube is lowered to arrange it below the plane of the surface of the liquid in the reservoir, whereupon the liquid is fed to the funnel and thence passes through the connected traps to the generator-pipe and enters the retorts of the generator to come in contact with the calcium carbide or other chemical contained therein. The gas generated in the retorts thence passes through the generator-pipe into the conveyer 27, thence into the inlet-pipe 4^a, and finally through the cooling-conductor 11 into the gasometer, and when the accumulation of gas in the gasometer has been sufficient to again raise the latter sufficiently to carry the discharge end of the feed-tube above the plane of the contents of the reservoir the supply of liquid will cease, and hence generation of gas will correspondingly be discontinued. From the gasometer the gas on its way to the main 8 passes through the down-conductor 12, wherein it is again exposed to the cooling action of the contents of the tank, and through the outlet-pipe 5, which forms one of the guides on which the gasometer operates.

Should the pressure of gas generated in the retorts exceed that for which the apparatus is adjusted, or, in other words, exceed the resistant pressure of the contents of the traps, the water will be backed out of the main trap 29 sufficiently to expose the extremity of the relief-tube 31, and an immediate reduction of pressure to the atmosphere will ensue; but the moment the pressure in the generator is reduced to normal the extremity of the relief-tube will be again sealed by the return of the water into the main trap from the auxiliary trap. It will be seen that the pressure in the auxiliary trap, which is exposed to the pressure in the generator, remains constant, the same not being in any way reduced by the forcing of the water out of the main trap, and owing to the location of the end of the relief-tube the contents of the auxiliary trap cannot be blown out, and therefore there is always a sufficient quantity of liquid in the auxiliary trap and under a normal pressure to seal the relief-tube, and thus prevent further escape of gas when the pressure of gas is reduced to the normal. From the foregoing description it will be seen, furthermore, that the operation of the apparatus cannot be initiated or gas cannot be generated until after the main and auxiliary

traps have been charged and sealed, thereby of course sealing the relief-tube, and hence the gas generated in the retorts, if within the pressure described as normal, must pass 5 through the channels provided therefor to the gasometer. Furthermore, should the contents of the first retort become exhausted that retort will become filled with liquid, thus expelling all the gas contained therein, before 10 the water will pass to the second retort of the series, whereupon when it is necessary to recharge the retorts it may be done without the loss of gas and without exposing the operator to danger incident to the liberation of surplus 15 gas which may be contained therein. Furthermore, it will be seen that the valves by which communication between the retorts and the generator-pipe is controlled are arranged in the branches, and therefore when 20 the solid contents of the retort have been exhausted the valve of that retort or in the branch with which that retort is in communication may be closed to cut that retort out of the series, whereupon it may be filled with 25 out danger to the operator. Furthermore, it will be seen that the supply of water or other liquid is at one end of the generator-pipe, while the escape of gas is at the opposite end, or, in other words, that the liquid and gas 30 traverse the generator-pipe in a common direction, and therefore when the gasometer is lowered to cause the flow of water into the generator-pipe said water first enters the first retort of the series and subsequently may be 35 carried by the pressure of the gas to the other retorts in succession to cause the simultaneous operation of all of the retorts; but when the solid contents of the first retort are exhausted a complete filling of said first retort 40 with water is necessary to cause the overflow to pass to the second retort of the series, and hence the gasometer will remain depressed until a sufficient amount of water has been supplied to fill the exhausted retort before 45 the liquid passes to the second retort to cause the generation of gas.

It will be understood that in practice various changes in the form, proportion, size, and minor details of construction within the scope 50 of the appended claims may be resorted to without departing from the spirit or sacrificing any of the advantages of the invention.

Having described our invention, what we claim is—

55 1. In an acetylene-gas apparatus, the combination with a generator, and a water-pipe, 17, communicating therewith, of a series of traps terminally in communication with each other and having a gas-relief at an intermediate point, the descending arm of the final trap connected to the pipe, 17, and the ascending arm of the receiving-trap provided with a supply-funnel adapted to maintain in

said final trap a sufficient volume of water to counteract the gas-pressure in the generator, 65 and a gasometer-controlled water-feed mechanism adapted to supply water in regulated volumes to the funnel and thence through the traps to the generator, substantially as described.

70 2. In an acetylene-gas apparatus, the combination with a generator, and a water-pipe, 17, communicating therewith, of a series of terminally-connected traps provided with a relief-pipe, 31, at the crown of the final trap, 75 the ascending leg of the receiving-trap provided with a funnel, 28, located above the traps and the descending leg of the final trap connected to the pipe, 17, to expose the liquid contents of the trap to the pressure of an excessive quantity of gas in the generator, and a gasometer-controlled water-supply mechanism arranged to discharge to the funnel, substantially as described.

80 3. An apparatus of the class described having a generator and a gasometer, a water-feed pipe, 17, and liquid-feeding devices comprising a liquid-reservoir, a flexible feed-tube in communication with said reservoir and terminally supported by the gasometer, connected main and auxiliary traps, the discharge-arm of the main trap being in communication with the feed-pipe, 17, and the generator, and the inlet-arm of the auxiliary trap terminating in a funnel, arranged in 90 proximity to the flexible feed-tube to receive water therefrom, and a normally-sealed vent in communication with the traps at an intermediate point, substantially as specified.

85 4. An acetylene-gas apparatus comprising 100 a gasometer, a generator having a water-feed pipe provided with depending branches and with retorts communicating with said branches, valves in the branches between the retorts and the water-feed pipe, a gas-pipe 105 communicating with the distant end of the water-feed pipe for conveying gas to the gasometer, liquid-feeding devices including a gasometer-controlled supply, a plurality of connected traps of which the discharge-arm 110 of the main trap communicates with the inner end of the water-feed pipe and the inlet-arm of the auxiliary trap is provided with a funnel situated above the series of traps and adapted to receive liquid from the liquid-feed 115 devices, and a vent communicating with the main trap at an intermediate point, substantially as described.

120 In testimony that we claim the foregoing as our own we have hereto affixed our signatures in the presence of two witnesses.
